(57) **CLAIM**

The ornamental design for a computer display system or portion thereof showing a graphical user interface having a three dimensional appearance as shown and described.

DESCRIPTION

The sole FIGURE is a computer display system or portion thereof showing a graphical user interface having a three dimensional appearance showing the claimed design.

The peripheral dashed broken lines in the FIGURE show the computer display system/device or portion thereof, and form no part of the claimed design.

The dashed broken lines within the peripheral dashed broken lines depict a boundary. The faded portion between the peripheral broken lines and interior broken line boundary form no part of the claimed design.
